(57) **CLAIM**

The ornamental design for an electric scooter, as shown and described.

DESCRIPTION

FIG. 1 is a perspective view of an electric scooter showing my new design;

FIG. 2 is a second perspective view thereof;

FIG. 3 is a front elevation view thereof;

FIG. 4 is a rear elevation view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of area "9" shown in FIG. 1;

FIG. 10 is an enlarged view of area "10" shown in FIG. 1;

FIG. 11 is an enlarged view of area "11" shown in FIG. 1;

FIG. 12 is an enlarged view of area "12" shown in FIG. 1; and,

FIG. 13 is an enlarged view of area "13" shown in FIG. 1.

The evenly broken lines shown in the drawings depict portions of the electric scooter that form no part of the claimed design. Additionally, the dot-dash broken lines around the enlargement indicia in FIGS. 1 and 9-13 are shown for the purpose of illustrating the bounds of the enlargements and form no part of the claimed design.

1 Claim, 13 Drawing Sheets
